UNITED STATES PATENT OFFICE.

MAX EMIL DEJONGE, OF FITCHBURG, MASSACHUSETTS.

DRYING-BOX.

No. 895,620.

Specification of Letters Patent.

Patented Aug. 11, 1908.

Application filed November 8, 1906. Serial No. 342,509.

To all whom it may concern:

Be it known that I, MAX EMIL DEJONGE, a citizen of the United States, residing in Fitchburg, in the county of Worcester and State 5 of Massachusetts, have invented an Improvement in Drying-Boxes, of which the following description, in connection with the accompanying drawings, is a specification, like letters on the drawings representing like

parts.

This invention relates to a fire-proof and insulated drying box or chamber, especially designed and adapted among other uses to be employed for drying paper or other material.

15 The present invention has for its object to provide a simple, inexpensive and efficient drying box, with which paper or like material may be most effectively dried at a minimum expense and in the least possible time, and 20 with which the danger of fire is reduced to a minimum and the temperature of the room or building in which the drying box is located is materially lowered and rendered healthy and comfortable for the operators.

25 In the present instance, the invention is shown as embodied in a drying box for drying paper in the form of a web, which is fed through the box by means of an endless apron, and provision is made as will be described, 30 for gaining access to the interior of the box at different points.

These and other features of this invention will be pointed out in the claims at the end of this specification.

35 Figure 1 is a side elevation of a drying box embodying this invention; Fig. 2, a plan view of the drying box shown in Fig. 1; Fig. 3, a cross-section on an enlarged scale, taken on the line 3—3, Fig. 1; Fig. 4, a detail in cross- 40 section of the supporting-frame; Fig. 5, an enlarged detail in section showing a portion of a top section and a side section, and Fig. 6, an enlarged detail showing a portion of the bottom section and a side section; Fig. 7, a 45 detail of a top section; Fig. 8, a detail of a side section, and Fig. 9, a detail to be referred to.

The drying box herein shown as embodying this invention, is made substantially oblong in cross section and comprises a top *a*, bottom *b*, and sides *c*, of a construction as 50 will be described, for imparting fire-proofing and heat-insulating properties to said box. For this purpose, the top, bottom and sides of the drying box are made of foraminous or reticulated metal, and one or more layers or 55 sheets of asbestos, mineral wool or like fire-

proof material. The top *a*, bottom *b* and sides *c* of the drying box are preferably made in sections to facilitate construction, repairs, etc., and each section may and preferably 60 will be made as shown in Fig. 7 and 8, and comprises one or more layers or sheets *d* of asbestos or other fire-proof material interposed between two sheets or layers *f*, *g* of foraminous or reticulated metal, such as wire-cloth or netting, which are firmly secured as by bolts or screws *h*, or otherwise to a metallic frame or skeleton comprising flat, longitudinal bars *i* and end bars *j*. The sections of the top *a* and bottom *b* of the box may be 65 constructed like the side sections, or they may be provided with angle iron ends *j* connected by tie rods 40, and may rest upon and be supported by longitudinally extended angle irons *k*, extended the length of the drying box and connected together by vertically arranged bars *l*, which may be fastened to the ceiling or other overhead support, and also by vertically arranged channel bars *m* extended to the floor *n* and forming support- 70 ing posts or legs for said box.

The supporting bars *l* on the opposite sides of the drying box may be connected together by tie rods *o* located above and below the box, (see Fig. 4).

85 The supporting bars *l*, *m* may be arranged and fastened to the angle iron bars *k* of the supporting frame for the box, so as to subdivide the space between the upper and lower longitudinal bars *k* into open sections, which 90 are closed by the side sections of the box, the longitudinal bars *i* of which are firmly secured to the supporting bars *k* by bolts, screws or rivets 10 (see Figs. 1 and 5). The end bars *j* of the side sections abut against 95 the supporting bars *l*, *m* to form a close joint.

The sections of the top *a* and bottom *b* of the box may be laid upon the horizontal portion of the angle irons *k* constituting the supporting frame for the box, after the manner 100 represented in Figs. 5 and 6. If desired the asbestos layers may be bound to the wire cloth by wire threads 12, represented in Figs. 5 and 6.

105 The drying box may be provided with end walls of a construction similar to the side sections, except that such end walls may be provided with suitable slots or openings, not shown, as they are well understood, for the passage of an endless belt, apron or carrier 110 for the paper to be dried on its passage through said box, the said endless apron

passing about suitable end rolls 15, 16, (see Figs. 1 and 2) located outside of the drying box and journaled in suitable brackets 17, 18, secured to a stationary support, the brackets 17 for the roll 15 being represented in Fig. 1 as secured to an extension of the main supporting frame, and the brackets 18 for the roll 16 being represented as secured to uprights 20. The roll 16 may be driven in any usual manner as by a belt 21.

The endless belt or apron 14 may be supported within the drying box by rolls 22, which are journaled in brackets or arms 23 secured as by bolts 24 to the supporting posts or legs *m* as represented in Figs. 1 and 9, and provision is made for gaining access to said supporting rolls through the side of the box. For this purpose, fire-proof doors 30 hinged at 31 are provided, which doors may be of the same construction as the side sections of the box.

The drying box is provided with suitable inlet and outlet openings for the circulation of hot air through the box, and not herein shown, as they may be of any suitable construction and are not necessary for the present invention, which relates to the structure of the drying box. The drying box may also contain the usual heating pipes, not shown.

From the above description, it will be seen that the paper or other material on its passage through the drying box may be subjected to a substantially high temperature and effectively dried in a minimum time, at the least possible expense, and with a minimum inconvenience to the operator, while at the same time the danger from fire is reduced to a minimum.

It will be observed, that the drying box is fire-proof, and at the same time heat-insulating, owing to its walls being practically formed of asbestos or like material, which material is held in place by a reticulated or foraminous metal frame, and this latter element enables the cost of the box to be materially reduced. Furthermore, it will be seen, that by preventing or largely reducing heat radiation, a less quantity of heat is required to dry the material, which enables the box to be made of minimum length, while at the same time, the temperature of the room in which the drying box is located is materially reduced, thereby enabling the operators to work with more comfort and at less danger to their health. It will also be observed that the sections comprising the top of the box rest upon the angle irons *k* and are capable of being lifted to uncover the top of the box more or less and provide vent openings for the heat, which enables the box to be used for drying paper requiring a high heat when the top is closed, and also to be used for drying paper which requires a materially less heat. The sections comprising the top may be made to perform the function of

valves to regulate the temperature within the box.

I have herein represented one construction of fire-proof drying box which I may prefer, but I do not desire to limit my invention to the particular construction shown.

Claims.

1. A drying box of the character described, having its top, bottom and side walls composed of sections, each comprising an open frame and a layer or sheet of heat insulating material, interposed between foraminous or reticulated metal sheets or layers secured to said frame, substantially as described. 75

2. A drying box of the character described, comprising longitudinally extended supporting bars, and sectional walls supported by said bars, the sections of said walls comprising an open metal frame, sheets of reticulated metal secured to said frame, and a layer or sheet of heat-insulating material interposed between said sheets of reticulated metal, substantially as described. 80

3. A drying box of the character described, comprising a skeleton frame composed of longitudinally extended bars, means to connect said bars together and walls for said skeleton frame composed of a plurality of open frames, reticulated metal sheets and a layer of fire-proof material secured to said open frames between said sheets. 90

4. A drying box of the character described, provided with longitudinally extended angle irons constituting a supporting frame, and walls supported by said frame and comprising sections composed of metallic side and end bars secured together and, foraminous sheets or layers of metal, and an interposed layer of heat-insulating material secured to said side and end bars, substantially as described. 100

5. A drying box of the character described, having walls thereof composed of sections, each comprising an open frame and a foraminous sheet of metal and a layer of heat-insulating material covering the openings in said metal sheet and secured to said open frame, substantially as described. 110

6. A drying box of the character described, provided with longitudinally extended angle irons constituting a supporting frame, top and bottom walls composed of sections resting upon said angle irons, and side and end walls composed of sections fastened to said angle irons, said sections being composed of foraminous metal and a layer of fire-proof material, substantially as described. 120

7. A drying box of the character described, comprising a metallic skeleton supporting frame composed of longitudinally extended bars arranged to form the corners of said box, and means for connecting said bars together, and a plurality of sections of fire- 125

proof and heat insulating material secured to said skeleton frame to form the walls of the box substantially as described.

8. A drying box of the character described, provided with longitudinally extended bars constituting a supporting frame, top and bottom walls composed of sections resting upon said bars, and side walls composed of sections fastened to said bars, said sections being composed of fire-proof and heat-insulating material, said top sections being capable of being removed to uncover more or less of the top of the box, substantially as described.
- 15 9. A drying box of the character described, comprising a skeleton supporting frame composed of longitudinally extended

bars, means to connect said bars together, side walls for said box composed of a plurality of sections of fire-proof material secured 20 to the side bars of said skeleton frame, and top and bottom walls supported by said frame and composed of a plurality of sections of fire-proof material, said top sections being capable of being removed to uncover 25 the top of the box more or less, substantially as described.

In testimony whereof, I have signed my name to this specification in the presence of two subscribing witnesses.

MAX EMIL DEJONGE.
